MERCURY SWITCH

Application filed December 10, 1931. Serial No. 580,164.

This invention relates to lever operated switches. More particularly it relates to a lever operated switch in which an electric circuit is made or broken by the movement of a body of mercury. It is an object of my invention to provide a lever operated switch which is quieter in operation than the lever operated switches hereinbefore known. Another object is to simplify the construction of lever operated mercury switches. Other objects and advantages of my invention will appear as it is described in connection with the accompanying drawing. In the drawing:— Figure 1 is a side elevation view partly in section of a switch constructed according to the principles of my invention. Figure 2 is an elevation section view, taken on a central plane through the switch shown in Figure 1. Figure 3 is a plan view of the switch shown in Figure 1. Figure 4 is a section view taken on the line 4—4 of Figure 3. Figure 5 is a plan view of the switch base. Referring to the drawing, the switch comprises a recessed switch base 10 having a hollow, oval, rearwardly-projecting portion 12 forming a well 14 for a movable mercury tube 16 hereinafter described. The switch base 10 is supported by a supporting strap 18 which has a rectangular aperture in its central portion through which projects the hand lever 20 of a switch actuating member 21. Adjacent each end and slightly to one side of the center line, the switch base 10 is provided with a recess 22 for the accommodation of two fingers 24 formed upon one side of the supporting strap 18 intermediate its ends and bent inwardly of the switch at right angles to the plane of the strap. These fingers 24 are formed only on one side of the strap and no accommodating recesses for them are formed in the base on the opposite side of the center line. Therefore the strap can only be assembled upon the switch base in one position. This is an important feature of the invention, since most mercury switches must be placed in a given position in order to be successfully operated. The switch supporting strap may be provided with a legend such as the word "top" upon its upper portion to aid in properly installing the switch. The switch actuator 21 is mounted for tilting movement on the switch base 10 by providing the base at each side of the mouth of the well 14 with a V shaped bearing surface or depression 30 and providing the switch actuator 21 with a pair of V shaped pivots 32 which are of less angular extent than the depressions 30 and are adapted to seat in the depressions 30. Above the switch actuator 21 is a spring 38 of resilient sheet metal which is provided with a central aperture 40 corresponding to the aperture in the supporting strap for accommodation of the hand lever 20. An extension 42 of the spring lies under the end portion of supporting strap 18 between it and the base 10, at the bottom of the switch. This extension 42 is provided with an aperture for the reception of the lower screw 44 by which the supporting strap 18 is held upon the switch base. The spring 38 is provided with a pair of spaced indentations 46 on each side thereof to accommodate two rollers 36 when the switch is in "off" and "on" position. The resilience of the spring is sufficient to impart a slight snapping movement when the switch is moved from "on" to "off" position and vice versa. In addition to its snapping function the spring also acts as a noiseless resilient stop to arrest the normal movement of the actuator between "on" and "off" positions. The rollers 36 are formed of a central disc portion and two opposed axial extensions forming the spindle of the roller. The rollers are loosely seated in cavities 34 located one on each side of the hand lever 20 in the outer surface of the actuating member 21. The cavities are similar in shape and slightly larger than one half the rollers, so that the rollers may be readily rotated therein. The use of the rollers is desirable because it tends to eliminate friction between the switch actuator and spring and thus makes for longer life of the switch. The rollers are held in the cavities 34 only by the spring 38 which is in turn held by the sup-

porting strap 18. Thus the supporting strap holds all the switch parts in assembled position.

A cover 48 of sheet insulating may be placed over the recess of the switch base and held in position by a supporting strap to keep dirt and foreign matter from the interior of the switch.

Mounted on the lower face of the switch actuator is a glass tube 16 having a pair of contacts (not shown) fixedly mounted therein and containing a body of mercury (not shown) which is adapted to move as the lever 20 is tilted from "on" to "off" position and vice versa to make or break an electrical connection between the two fixed contacts in the tube. This tube forms no part of my invention and therefore need not here be described in further detail. It will suffice to say that anyone of a number of well known tubes could be adapted for use in connection with my switch mechanism.

The glass tube 16 is held to the switch actuator by means of a cradle 50 which is stamped from sheet metal and attached, by screws or otherwise, to the actuator 21 and has arms 52 which embrace the tube. The fixed contacts of the tube are connected by flexible leads 54 to wire terminals 56, 56' located on one side of the switch base at opposite ends thereof whereby the switch may be connected in an electric circuit. Since the cradle 50 may, in most cases, be made of metal, and the leads 54 may be uninsulated it is desirable to keep the leads out of the switch well 14 so as to avoid their contacting with the cradle. I accomplish this by providing a pair of channels 57, 57' extending transversely of the switch base on opposite sides of the switch well, one (57) leading from one of the wire terminals 56 and the other (57') from the other terminal 56'. The slack of the leads is taken up by looping them around in the channels 57, 57'. With this construction it is possible to assemble the wire terminals with the leads and the movable parts of the switch and lay them all as a unit in the switch base, thus simplifying the assembly of the device as well as protecting the leads.

In operation as the hand lever 20 is tilted from the position shown in full lines in Figures 1 and 2, to the position shown in dotted lines in Figure 2, the switch will be moved from "on" to "off" position and as it is again moved back to the full line position it will again close the circuit.

It is worthy of mention that the V shaped pivot for the switch actuator is especially advantageous in this type of switch because it prevents overthrow of the actuator by reason of the sides of the V shaped pivots 32 of the actuator engaging with the sides of the bearings or depressions 30, thus preventing the glass tube from being pressed against the

wall of the well 14 in case of an attempt to push the switch beyond the normal "on" or "off" position as defined by a leaf spring.

Many changes and modifications of my invention will occur to those skilled in the art, therefore I do not limit myself to the specific form of the parts as shown.

I claim:

1. A mercury switch comprising an insulating base having a pair of V-shaped bearings therein, a tiltable switch actuator having V-shaped pivots fitting in said bearings and having a lever portion extending therefrom whereby said actuator may be manually moved, a cradle secured to said actuator, a receptacle held in said cradle and containing a body of mercury and a plurality of contacts for making and breaking an electric circuit.

2. A switch comprising an insulating base, a switch actuator pivotally mounted in said base and having a lever portion extending therefrom for manually actuating the switch, a leaf spring secured above said actuator, rollers loosely mounted in cavities in said actuator and held therein by said spring, said spring having a plurality of indentations for said roller to hold said actuator in "on" and "off" positions in combination with circuit making and breaking means carried by said actuator.

3. A switch comprising an insulating base, a switch actuator pivotally mounted in said base and having a lever portion extending therefrom for manually actuating the switch, a leaf spring secured above said actuator, rollers loosely mounted in cavities in said actuator and held therein by said spring, said spring having a plurality of indentations for said roller to hold said actuator in "on" and "off" positions, in combination with a receptacle mounted on said actuator and provided with a pair of contacts and containing a body of mercury which is adapted to make and break electrical connection between said contacts.

4. A mercury switch comprising an insulating base, a switch actuator pivotally mounted on said base and having a lever portion extending therefrom for manually actuating the switch, a leaf spring above said actuator, rollers loosely mounted in cavities in said actuator and engaging with said spring, a supporting strap for said base serving to hold the parts of said switch in assembled position, said spring having a plurality of indentations for said roller to hold the switch in "on" and "off" positions, and circuit making and breaking means including a body of mercury mounted upon said actuator.

5. A mercury switch comprising an insulating base having a pair of V-shaped bearings therein, a tiltable switch actuator having V-shaped pivots fitting in said bearings

and having a lever portion extending therefrom whereby said actuator may be manually moved, a cradle secured to said actuator, a receptacle held in said cradle and containing a body of mercury and a plurality of contacts for making and breaking an electric circuit, a spring above said actuator, rollers loosely mounted in cavities in said actuator and engaging said spring, said spring having indentations for said rollers, and a supporting strap for said base serving to hold all said parts in assembled position.

6. In a mercury switch, a recessed insulating base, mercury circuit making and breaking means contained therein, a base supporting strap having a legend thereon, said strap being provided with means permitting its assembly upon said base in one position only.

20 7. A mercury switch comprising an insulating base, switch actuator bearings and lead wire channels molded therein, a manually operated switch actuator pivoting in said bearings, a mercury container mounted 25 on said actuator having a plurality of fixed contacts connected to said container lead wire terminals mounted on said base, flexible lead wires, said flexible lead wire connecting the fixed contacts and wire terminals and seated 30 in said channels.

8. A switch comprising an insulating base, lead wire channels extending transversely in said base, a manually operated switch actuator, circuit making and breaking means carried by said actuator, flexible lead wires connected to said means, wire terminals mounted on the base, said flexible lead wires being connected to said terminals and being seated 35 in said channels.

40 9. A mercury switch comprising an insulating base having molded bearings therein, a molded switch actuator having integral pivots pivoting in said bearings, a lever portion to manually move said actuator, a cradle 45 secured thereto, in combination with mercury circuit making and breaking means carried by said actuator.

In testimony whereof I have signed my name to this specification.
